UNITED STATES PATENT OFFICE.

HENRY M. JACOBS, OF WAYNESBURG, PENNSYLVANIA.

WAGON-SEAT SUPPORT.

SPECIFICATION forming part of Letters Patent No. 258,303, dated May 23, 1882.

Application filed May 6, 1880. Renewed April 17, 1882. (Model.)

To all whom it may concern:

Be it known that I, HENRY M. JACOBS, a citizen of the United States, residing in Waynesburg, in the county of Greene and State of Pennsylvania, have invented certain new and useful improvements in wagon-seat bearers for supporting the seat above the wagon-body and for its convenient removal therefrom; and I do hereby declare that the following is a full, clear, and exact description of the invention, which will enable others skilled in the art to which it appertains to make and use the same, reference being had to the accompanying drawings, which form a part of this specification, and in which—

Figure 1 shows a side elevation of the front end of a wagon-body with my improved seat-bearer attached thereto, and supporting an elliptical spring-seat thereon. Fig. 2 is a perspective view of that part which is fastened to the wagon-body, and forming a socket for the seat-bearer B to enter through the hole G. Fig. 3 shows a back side or rear view of the same with the supporting-iron B inserted, showing the rear opening of the front projection, m, shown in Fig. 2. Fig. 4 shows a vertical cross-section of the socket on the line y y, Fig. 3. Fig. 5 shows a vertical section on the line x x of Fig. 4, showing the form of the internal cavity and of its walls. Fig. 6 shows the form of the notches in each side of the bottom of the standard or upright bearer B. Fig. 7 is a view similar to Fig. 5, but with the internal cavity modified in form, and with the end of B modified correspondingly, as further shown in Fig. 8, which otherwise corresponds with Fig. 6. Figs. 9 to 12 show modifications of the top end of the seat-bearer B, for the purposes hereinafter described.

The same letters show like parts in each figure.

The object of my invention is to produce a cheap, ornamental, durable, and more convenient seat-bearer than any heretofore made. It is so constructed that it stands firmly in position with bearings of iron upon iron, and so that the whole seat with the attached bearers may be lifted clear out of the iron sockets and off the wagon without having to unfasten any clamps, screw-bolts, or anything else, but to

simply lift it out; or it may be lifted up partly out of the sockets, then turned over in an inclined position out of the way, either backward or forward, for convenience in loading or unloading the wagon, as indicated by the dotted lines in the drawings.

Both parts of my improved seat-bearer are made preferably of malleable cast-iron, of a size requisite to give the proper strength, and are so constructed that they are easily molded in a one-parting flask without requiring dry cores, and may be supplied in quantity to the hardware trade all ready to attach to wagons. The standard or bearer B, when used in connection with an elliptical spring, is forked, with the two branches curved in any ornamental shape to give the requisite length, and to fit the spring where the bolts clamp them together as shown in Figs. 1 and 7; or where it is desired to have the seat lower down it may be made in the form shown in Fig. 3; or, if desired to be used without springs, it may be made, as shown in Fig. 12, and the straight horizontal top bolted directly to the seat-bottom. Through the top portion of each of the forked curved arms are elongated holes or slots for inserting the screw-bolts for clamping the elliptical springs to them, as shown in Fig. 1. These holes are elongated into slots to accommodate the slight variation in the distance apart of the two bolt-holes in the springs of different manufacture. The branching curved arms, being made of good quality of malleable iron, may also be bent sufficiently to accommodate the requirements of different springs.

The hollow cavity of the socket is cast with an open bottom, so that sand or dirt cannot accumulate in it, and a projecting lug, g, is provided a suitable distance below it for a stop or bearing for the protruding end of the seat-bearer B to rest upon; or, instead of the lug g to support the weight of the seat, there may be projecting lugs f, as shown in Figs. from 7 to 12, which rest upon the correspondingly-curved bearings e to support the weight of the seat. The objects of curving or sloping the top of the bearing e are, first, that the sloping lugs f will wedge solidly down upon or between them and not shake or rattle; and, secondly, by taking off the square inner upper

corners of *e e* it requires correspondingly less depth of the notch *a* in bearer *B* (which is thus less weakened) to allow it to turn down to the same angle.

5 When the lugs *f* rest upon *e*, or the bottom of *B* is on *g*, the flat bearings *b b* have bearing against the narrow part of the socket near its bottom. The rear or inside face of *B* rests against the flat portion of the socket-plate at 10 *n* above and also at *n'* below the hollow cavity of the socket, Figs. 2 and 4, and the front or outside face of *B* bears against the inside face of *m*, thus giving *B* a loosely-fitting bearing upon all sides.

15 The seat may be lifted off entirely by simply lifting it up vertically until the seat-bearers *B* draw out of the sockets; and it may be replaced by simply entering the ends of the seat-bearers *B* into the socket-holes *G* and letting 20 it drop to its place.

If it is desired simply to turn the seat over out of the way, backward or forward, as shown in dotted lines in Fig. 1, each end of the seat is raised up slightly, and at the same time 25 leaned or pressed slightly backward or forward, as it is desired to go, and whenever the notch *a* in the side of *B* comes opposite to *e* it drops over upon it in the position shown by dotted lines in Fig. 5, the projection *b* coming 30 against the under side of *e*, which thus acts as a stop to prevent further upward motion when it rolls or turns upon *e* as a fulcrum or hinge until the notch *c* strikes upon the opposite *e*, stopping further motion when it occupies the 35 position shown by broken lines in Figs. 5 and 7, and by dotted lines in Fig. 1.

In the slight modification in the form of the socket in Fig. 7, and the corresponding modification of *B* shown in Figs. 7, 8, &c., the parts 40 are so proportioned that when the notch *a* comes opposite *e* at the same time the projection *d* has passed into the enlargement of the cavity *m*, so that a little side pressure as it is drawn up causes it to drop over and catch upon 45 *e*, as shown in dotted lines in Fig. 7, (without having to take the oblique position before it catches, as in the form in Fig. 5,) which makes it more convenient and more certain to catch solidly upon *e*, after which it is turned over till 50 the notch *c* in the other edge strikes upon the opposite *e*, as in the first-described modification.

When it is desired to use spiral springs,

which are cheaper and occupy less space than elliptical springs, they may be used as shown 55 in Fig. 9 or 11, or by other modified forms of the top end of the bearers *B*. In Fig. 9 the top of *B* is elongated into a straight bar, *B'''*, over which is slipped the casting shown in Fig. 10, *B'''* passing up through the hollow boxes *D'*, which prevent the seat from rocking or tipping, and the cross-piece *D''* furnishes proper support for the seat-bottom, as shown, the spiral spring being secured to the top of *B'''* and coiled around it, as shown by dotted 60 lines, with its bottom end secured to *D*, which, with the seat, thus becomes suspended by the spring from the top of *B'''*. In Fig. 11 the **T**-shaped piece *C* slides through the inclosing bearings *B''* on the top of *B*, and the spiral 65 spring surrounds them, as shown by dotted lines, and supports the seat upon the top of *C*. 70

I am aware that seat-bearers have been made of both wood and of iron to lift out of staples, but without means of turning over in 75 inclined positions, backward and forward, as mine does. I am also aware that seat-bearers have been made with a securing-bolt through the bottom of the seat-bearer and through the side of the wagon-body, so as to turn over in one direction, and also of spring-seats to turn over in one direction, but each of which cannot be entirely removed without first removing bolts, all of which are quite different from mine, and none of which I claim; but 85

I claim—

1. The metal seat-bearer with the notches in its lower end for catching upon corresponding projections in the seat-bearing socket, for the purpose and substantially as set forth. 90

2. The inwardly-enlarged cavity in a metal seat-bearing socket, in combination with the interiorly-fitting notched end of the seat-bearer, for the purpose set forth.

3. The lug *g*, in combination with the notched metal seat-bearer *B* and inwardly-enlarged cavity *m*, for the purpose set forth. 95

4. The elliptical spring secured to the curved arms of the wagon-seat bearer *B*, with the notches *a a* and *c c*, in combination with the socket-plate having inwardly-enlarged cavity *m* and bearings *e e*, substantially as shown. 100
